UNITED STATES PATENT OFFICE.

ADELBERT L. TRAVER, OF PHILMONT, NEW YORK.

LOOP-SEWING MACHINE.

Application filed August 28, 1919, Serial No. 320,491. Renewed June 8, 1923.

To all whom it may concern:

Be it known that I, ADELBERT L. TRAVER, a citizen of the United States, and a resident of the city of Philmont, county of Columbia, 5 State of New York, have invented a new and Improved Loop-Sewing Machine, of which the following is a full, clear, and exact description.

This invention relates to sewing machines, 10 and more particularly to loop sewing machines for joining knitted fabrics. The invention directly appertains to a looping machine used in joining knitted cuffs and knitted parts of wearing apparel to other parts 15 of knitted wearing apparel.

An object of the invention is to provide a simple and effective looping machine used for the purposes of joining or sewing knit cuffs and armlets, sleeves and the like to the 20 arms and body portions of knit goods or wearing apparel.

It is an object to provide a loop sewing machine upon which may be mounted the knit garment and knit armlet to be fastened 25 or joined to said garment.

It is a further object to provide a loop sewing machine provided with a set of thread carrying needles together with a stitch finger, and so arranged as to pass a 30 loop of thread through the garment and through the armlet in order to adequately join the two parts together. It is also a purpose to disclose a machine employing two threads in order to form an overstitch 35 through the two loops of the knitted fabrics to be joined together; and to provide a loop sewing machine which may be driven at a high rate of speed and be free from skipping stitches.

40 And it is a further purpose to provide a sewing machine of this character, and for accomplishing the above desired purposes; which will be comparatively simple in construction, inexpensive to manufacture, and 45 simple in operation.

With the above principal objects in view and others, the invention has relation to the arrangement and combination of sewing machine parts as set out in the several appended claims, described in the following 50 specification, and portrayed in the accompanying drawings, wherein:

Figure 1 illustrates a plan view of the loop sewing machine.

55 Figure 2 illustrates the machine in side elevation.

Figure 3 shows the loop sewing machine in side elevation, a part thereof in section, and other parts removed. This view presents a different setting or position of the 60 sewing needles from the other views in the drawings.

Figure 4 illustrates a fragmentary plan view enlarged in detail in order to bring out the impaling points and positions assumed 65 by the sewing needles with reference to the points.

Figure 5 illustrates still another fragmentary view with a progressed setting or different position of the needles in the cycle 70 of operation of the machine.

The remaining figures of the drawings namely, 6, 7, 8, and 9, illustrate various positions in the cycle of operation of the needles. The different positions of the needles will 75 more clearly appear as the description continues.

A loop sewing machine built according to the plans of this invention employs the usual form of step-by-step rotating impaling 80 fringe to hold the garments to be joined together. A stitch finger is mounted on a frame and disposed above and close to the two parts of knit fabric to be joined together. A pair of cross actuated thread carrying needles are moved transversely of the 85 stitch finger, one needle above said finger and the other needle below said finger to form an overstitch link through the loops of the two knit fabric pieces to be joined. 90

Referring now more in particular to the drawings, the numeral 14 designates a base or bolting plate upon which is mounted a frame arm 15. The frame arm holds a vertical stem 16, and the stem supports a circular plate frame 18.

A shaft 19 is journaled in brackets 20, said brackets being secured to the underneath side of the circular frame plate 18. A slotted opening 21 is formed in the frame, and a ratchet wheel 22 is fixed upon the shaft and projects through the opening 21 so as to expose a portion of the ratchet wheel above the frame plate. A pinion 24 is fixed on the shaft 19, and meshed with a 100 ring gear 25. The ring gear 25 is rotatably carried on the periphery of the circular frame plate, and driven step-by-step by the pinion 24 which is rotated by mechanism provided to actuate the ratchet wheel 22 as 105 later seen.

A power shaft 27 is journaled in the

frame arm 15. An idle pulley 28 is journaled on the power shaft, and a power pulley 29 is fixed on the shaft. An eccentric cam 30 is fixed to the shaft, and an eccentric strap 31 rotatably carried on the eccentric 30. The eccentric strap 31 has connected thereto a rod 32 which reaches rearwardly and terminates above the ratchet wheel 22. A dog 33 is fixed to the outer end of the rod and engages the ratchet wheel 22. When the power shaft 27 is driven through a belt applied to the power pulley the eccentric 30 drives the rod 32 and imparts a step-by-step rotation to the ratchet wheel which rotates 15 the ring gear 25.

A fringe of impaling points 35 is carried by the ring gear and disposed radially on the periphery thereof and travels step-by-step with the ring gear. This fringe of impaling points is secured to the ring gear in the usual manner, and the impaling pins are grooved along the upper face thereof as shown in the detail views Figures 6 to 9, as is the usual case with the impaling fringe 20 employed on machines of this character. A guard ring 36 is concentrically disposed and slightly spaced from the ring gear. Brackets 37 are secured to the circular frame plate and reach over the impaling fringe to support the guard ring. This ring is employed 25 for the purpose of guiding the impaled fabric through the stitching mechanism as later seen, and for the purpose of protecting the delicate points of the impaling fringe exposed to view on the operator's side of the machine where the knit fabric is pushed up on the impaling fringe. In Figure 1 the impaling fringe or impaling points which received the two knitted fabrics to be joined 30 together are shown with said fabrics impaled or thrust upon the points.

A loop finger 39 is adjustably retained in an arm 40. The arm is mounted on the circular frame plate, and is provided with 45 an adjusting screw 42 which holds the loop finger 39 in any adjusted position. The loop finger is applied tangentially to the perimeter of the ring gear which disposes it transversely over the impaling points.

50 A stem 43 is fixed to a bolting bracket 44, and the bracket is secured to the frame 15. This disposes the stem 43 outwardly from the frame to pivotally mount a bell crank comprising arms 45 and 46. The power shaft 27 is fitted with an eccentric 48, and a strap 49 is journaled thereon. The strap connects with a link 50, and the link 50 connects with the bell crank arm 46. The lower bell crank arm 45 is fitted with a stitch 55 needle 51. As the power shaft 27 is driven the bell crank 45-46 is actuated which causes the stitch needle 51 to travel back and forth underneath the loop finger 39.

55 A bracket 53 is secured to the frame 15 as an integral part therewith. The lower

portion of this bracket pivotally carries a bell crank comprising arms 54 and 55. The upper end of the bell crank arm 55 is fitted with an actuating rod 57 and the outer end of this rod pivotally connects with the upper end of the bell crank arm 46. In this manner motion is transmitted from the bell crank arm 46 to the bell crank 45-55. The outer adjacent ends of the arms 45 and 54 travel in synchronism, that is to say, the outer end of the arm 54 oscillates in a vertical plane in front of the impaling fringe and the lower end of the arm 45 oscillates in a vertical plane over and approximately parallel to the radially disposed pins of the 60 impaling fringe.

The outer end of the arm 54 pivotally mounts a rocker shaft 59. The rocker shaft is journaled in the arm and projects to each side thereof, and one end is fitted with a 65 looper needle or hook 61, and on the other end of the rocker shaft is fixed a rocker arm 62. A link 63 connects the outer end of the rocker arm 62 with the lower end of the bell crank arm 45. Each end of the link 63 is 70 pivotally connected with the members 62 and 45. This arrangement causes the rocker arm 59 to be oscillated back and forth or to be rocked as the bell crank arm 46 is driven from the eccentric 48. This causes the looper needle 61 to oscillate about the axis of its shaft 59 as the bell crank arm 54 moves up and down. The looper needle 61 is made with a suitable curvature near the outer end 75 thereof and is provided with the necessary 80 guide holes for carrying thread. Suitable thread guide members are provided and appropriate thread tension members are fitted to the machine. Tension discs 70 are mounted on an arm 71 and guides the 85 thread 72 to the stitch needle 51. Likewise a tension 73 guides thread 74 to the looper 90 needle 61.

In the use of this machine, an operator 95 impales the fabric garment 76 and the fabric cuff or sleeve 77 upon the impaling fringe or impaler pins 35. This is brought out in the several Figures 6 to 9, and shows two pieces of knit fabrics placed on the impaling fringe to be joined together by thread passed 100 through the loops and knotted by the co-operative action of the several needles. The operator continually places the knitted fabrics upon the impaling fringe as the ring gear and fringe continues the step-by-step 105 rotation. The guide 36 brings the two loops of the two knitted pieces into proper relation with the needles.

110 As the impaling fringe together with its knitted fabric revolves step-by-step, the two needles 51 and 61 synchronously operate due to the positive link connection formed by the two bell crank members. 115 The link 57 impresses an oscillating action 120 into the bell crank 45-55, while the link 63 125

130

impresses a rotary motion upon the rocker shaft 59. For this reason the looper needle 61 rises and recedes in a continual oscillating motion over the loop finger, while the 5 stitch needle oscillates back and forth concentrically with the axis of the bell crank 45—46 underneath the loop finger 39. The stitch needle therefore, passes its thread 72 underneath the loop finger while the looper 10 needle passes its thread over the loop finger.

The various positions occupied by the needles during their cycle of operation are shown in the several figures from 6 to 9. In these figures it will be seen that the needle 15 51 in its forward stroke enters the loop of thread presented by needle 61, and in turn that needle 61 in its up stroke enters the loop of thread sent by needle 51, thus forming the stitch which is the common two-thread- 20 over-edge stitch now in common use. In Figure 6 it will be seen that the needle 61 is just entering the loop presented by needle 51. As the machine continues to operate the needles gradually move to the position 25 shown in Figure 7 and then to Figure 8. The travel of the needle 61 is in the path of an arc, upwardly and over the loop finger 39 and over the path of travel of the needle 51. As the needle 61 moves back on its re- 30 turn stroke, a loop will be presented to needle 51 which immediately enters the loop and then passes beneath the loop finger 39 as indicated in Figure 9. The parts move from this position for the full distance of their 35 travel and then on the return movement assume the position shown in Figure 6. The particular stitch provided is a well known stitch but the way in which the needles 51 and 61 are arranged and the particular 40 way in which they operate together with the mechanism for actuating the same are different from those heretofore provided.

The knitted fabric parts are thus joined together and removed from the impaling 45 fringe after the fabric parts have passed from beyond the range of the guard 36 on the other side of the machine.

This loop sewing machine is presented to fulfill the need felt for a high speed loop 50 sewer useful in the operation of joining knitted fabrics.

Having thus described my invention, what I claim as new and desire to secure by Letters Patent is:

55 1. A loop sewing machine, comprising in combination; a suitable frame, a ring gear rotatably carried on the frame, impaling fringe radially disposed on the ring gear, a step-by-step driving mechanism adapted 60 to rotate the ring gear and impaling fringe, bell crank members pivoted on the frame, a needle carried by one bell crank, and a rocker shaft carried by the other bell crank, a needle fixed to the rocker shaft, a driving mechanism provided to oscillate 65

the bell cranks, and a link associated with the rocker shaft and one of the aforesaid bell cranks to oscillate the rocker shaft.

2. A sewing machine, and stitch mechanism, comprising in combination; impaling fringe upon which is threaded knit fabrics to be stitched, a loop finger mounted in a fixed position above the impaling fringe, a stitch needle provided to move back and forth under the loop finger, a bell crank 70 pivotally carried on the frame, a rocker shaft journaled in the bell crank, a looper needle fixed to the rocker shaft, a link attached to the rocker shaft, suitable mechanism employed to move the link to oscillate the rocker shaft to cause the looper needle to move transversely over the loop finger, and suitable driving mechanism employed to operate the parts.

3. A sewing and stitching mechanism, comprising in combination; a frame, a drive shaft journaled in the frame, a bell crank pivoted to the frame, an eccentric to drive the bell crank, a needle carried on the bell crank, and another bell crank pivoted on the frame, a link pivotally joining the two bell cranks in order that the first named bell crank may impart an oscillating motion to the second named bell crank, a 85 rocker shaft journaled in the last named bell crank, a link connected with the rocker shaft and connected with the first named bell crank to impart a rocking motion to said rocker shaft, and a looper needle mounted on the rocker shaft to oscillate with the rocker shaft and co-operate with the first named needle to execute stitch operations.

4. A stitching mechanism, comprising in combination; a frame, a pair of bell cranks 90 pivotally mounted thereon, a stitch needle mounted upon one end of a bell crank, and a link mounted upon the other end of this bell crank, another bell crank connected with the link to be oscillated therefrom, a rocker shaft journaled in the second named bell crank, a rocker arm fixed to the rocker shaft, a link pivotally connected with the rocker arm and pivotally connected with the first named bell crank to oscillate the rocker shaft, and a looper needle mounted on the rocker shaft to oscillate in co-operation with the stitch needle.

5. A stitching mechanism, comprising in combination; a frame, a pair of bell cranks 105 pivotally mounted thereon, a stitch needle mounted upon one arm of one bell crank, and a link mounted upon the other arm of this bell crank, another bell crank connected with the link to be oscillated therefrom, a rocker shaft journaled in the second named bell crank, a rocker arm fixed to the rocker shaft, a link pivotally connected with the rocker arm and pivotally connected with the first named bell crank to 110 oscillate the rocker shaft, and a looper 115 needle

120

125

130

needle mounted on the rocker shaft to oscillate in co-operation with the stitch needle, and a loop finger transversely disposed across and between the stitch needle and looper needle.

6. A stitch mechanism for sewing machines comprising: a pair of bell cranks comprising radial arms said bell cranks pivoted and adapted to be oscillated, a link connection established between two arms of the bell cranks, a needle carried on one bell crank, and a needle carried on the other bell crank, and means associated with one bell crank for oscillating the needle carried on the other bell crank.

7. A stitch mechanism for sewing machines comprising: a pair of bell cranks consisting of radially disposed arms suitably pivoted, a link connection established be-

tween two of the radial arms of the bell cranks, a needle swingably carried on one arm of one bell crank, a link associated with said needle and associated with one of the aforesaid bell cranks to produce oscillation of the needle and a needle carried by the other of said bell cranks.

8. In stitching mechanisms for sewing machines comprising: pivoted bell cranks suitably oscillated, a rocker shaft journaled in one bell crank, a rocker arm fixed to the rocker shaft, a connecting link established between the rocker arm and one of the bell cranks to oscillate the rocker shaft, and a needle mounted on the rocker shaft, and another needle carried on the other bell crank.

ADELBERT L. TRAVER.
